U.S. application No. 09/216,889, a utility application filed by the applicant on Dec. 18, 1998.

Primary Examiner—Robin V. Taylor

Attorney, Agent, or Firm—Kenneth L Tolar

[57] CLAIM

The ornamental design for a water display system, as shown and described.

DESCRIPTION

FIG. 1 is a perspective view of the display system installed on the bottom of a swimming pool, the swimming pool bottom depicted in phantom and forms no part of the claimed design. The water distribution equipment and piping is installed beneath the pool bottom and is therefore concealed.

FIG. 2 is a perspective view of the water display system.

FIG. 3 is a top view of the water display system.

FIG. 4 is a bottom view of the water display system.

FIG. 5 is a front view of the water display system.

FIG. 6 is a rear view of the water display system.

FIG. 7 is a left side view of the water display system; and, FIG. 8 is a right side view of the water display system.
